US00D929365S

(12) **United States Design Patent** (10) **Patent No.:** **US D929,365 S**
(45) **Date of Patent:** **** Aug. 31, 2021**

(54) **HEADPHONES**

(71) Applicant: **Logitech Europe S.A.**, Lausanne (CH)

(72) Inventors: **Maxime Dubreucq**, San Francisco, CA (US); **James Lee Kwon**, Oakland, CA (US); **Tony Mankit Kan**, Burlingame, CA (US); **Nicolas Metral**, Lausanne (CH); **William Carey**, San Francisco, CA (US)

(73) Assignee: **Logitech Europe S.A.**, Lusanne (CH)

(**) Term: **15 Years**

(21) Appl. No.: **29/758,031**

(22) Filed: **Nov. 11, 2020**

Related U.S. Application Data

(63) Continuation of application No. 29/683,666, filed on Mar. 14, 2019, now Pat. No. Des. 905,659.

(57) **CLAIM**

The ornamental design for headphones, as shown and described.

DESCRIPTION

FIG. 1 is a front, left side perspective view of headphones showing our new design;

FIG. 2 is a front, right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a right side sectional view taken along line 9-9 of FIG. 1; and,

FIG. 10 is a left side sectional view taken along line 10-10 of FIG. 2.

The broken lines shown to be immediately adjacent to the shaded/contoured areas represent certain portions of the bounds of the claimed design while all other broken lines are directed to environmental features and are provided for illustrative purposes only; the broken lines form no part of the claimed design.

1 Claim, 9 Drawing Sheets
